LIMITED-CUT-OFF STEAM ENGINE

Application filed November 16, 1927. Serial No. 233,577.

This invention relates to what is known in the art as a limited cut-off steam engine and is particularly applicable to limited cut-off locomotives.

- 5 In locomotives of this type the valves and operating mechanism therefor are arranged so that in what would ordinarily be "full gear" position cut-off will occur at the main steam ports at some percentage of the stroke 10 of the piston materially less than heretofore customary, say for example 50%. With such an arrangement of the valves and valve operating mechanism there are, of course, positions in which the engine may stop where 15 the turning moment is insufficient for starting.

In order to effect a start it has been customary to provide what are known as auxiliary or starting ports adapted to deliver 20 steam to the cylinders after cut-off at the main port. These starting ports are ordinarily of relatively small capacity with the idea in mind that as the speed of the engine increases the amount of steam delivered 25 therethrough will gradually become of less and less consequence.

It is now coming to be recognized, however, that in order to have an engine which will be capable of "snappy" starting it is 30 necessary to make the auxiliary or starting ports of substantial capacity. This makes the flow of steam thru them a matter to be considered at all speeds of the engine especially where no provision is made for preventing pre-admission of the steam thru the starting ports. Pre-admission takes place, it will be understood, thru the starting ports before admission at the main ports and becomes a substantial factor in decreasing the 40 power out-put of the engine during the compression period of each stroke of the pistons.

With the foregoing in mind the object of our invention can be better understood and it can be stated as involving a means for 45 minimizing the deleterious effect of pre-ad-

mission by providing a by-pass for the steam which will connect the compression side of the piston to the expansion side.

The foregoing object together with more specific objects which will appear in connection with the following description are attained by means of the various preferred embodiments of the invention illustrated in the figures on the accompanying drawing, where-
in

55 Fig. 1 is a vertical longitudinal section thru a portion of the cylinder and valve chest of a steam engine equipped with our invention;

60 Fig. 2 is a similar view illustrating another manner in which the invention may be carried out;

65 Fig. 3 is another similar view illustrating a third way in which our invention may be carried out;

70 Fig. 4 is a fragmentary view similar to Figs. 1 to 3 inclusive illustrating still another method of carrying out our invention;

75 Fig. 5 is a fragmentary view of the cylinder and piston of a steam engine illustrating one more way in which we may carry out our invention.

The several figures all represent typical locomotive construction and the invention will be described as applied to a locomotive.

80 The cylinder 1 is supplied with steam from the valve chest 2 thru the customary main steam passages 3 and 4. The main ports 5 and 6 leading respectively to the passages 3 and 4 thru the valve chest bushing 7 are under the control of the customary piston valve 8. It will be understood, of course, that the valve together with its operating mechanism or valve gear (not shown) is arranged to cut off the main port so that the supply of steam will be continued for a portion only of the stroke of the piston 9 which, in this instance, will be assumed to be at 85 50% of such stroke. Furthermore the valve 90

illustrated is what is known as the inside admission piston type with the exhaust taking place at the ends.

In order to start the locomotive the auxiliary passages 10 and 11 are provided which respectively connect the main passages 3 and 4 with the starting ports 12 and 13, the starting ports being located inside of the main ports 5 and 6 so that they will receive steam after cut-off at the main ports.

In the several figures the piston 9 is illustrated as traveling toward the right in the direction of the arrow. The admission of steam thru the passage 4 and port 6 has not yet begun and compression is taking place at the right of the piston 9. But during this period of compression, communication with the source of steam supply can take place thru the port 13 and auxiliary passage 11 since the valve 8 has uncovered the port 13.

This pre-admission or communication with the steam supply thru the starting port is, of course, objectionable in direct proportion to the capacity of the starting port.

In order to overcome or minimize the deleterious effect of this pre-admission, we provide means for by-passing the steam to the expansion side (the left-hand side) of the piston. In the arrangement of Figure 1 this is accomplished by means of the auxiliary passage 14 which directly connects the starting passage 11 with the cylinder 1 thru the port 15 in the cylinder bushing 16. At the opposite end, of course, there is a corresponding passage 17 extending from the starting passage 10 to the cylinder thru the port 18 in the cylinder bushing.

This arrangement will cause a slight waste of steam which, however, is more than offset by the advantage to be derived by minimizing the effect of pre-admission. Furthermore, at very high speeds of the engine both pre-admission and wastage are of materially less consequence and at starting some wastage may be permitted in order to obtain the advantages of quick and "snappy" starting.

The same principle is involved in each of the other figures in the drawing although the method employed in each instance is slightly different. In Fig. 2 the by-pass 19 consists of a groove or passage cut in the outer face of the cylinder bushing. In Fig. 3 it consists of a passage 20 which connects the main passage 4 with the cylinder on the expansion side of the piston. In Fig. 4 the passage 21 consists of a groove or channel on the inside of the cylinder bushing extending between the main passage 4 and the port 15. In Figure 5 a pipe 22 is provided on the outside of the cylinder which connects the port 15 on the expansion side of the piston with another hole 23 on the compression side.

We claim:—

In a steam engine the combination of a cylinder, a piston, a valve chest, a valve, a main steam supply passage, an auxiliary steam supply passage which receives steam after cut off at the main passage, and a passage for delivering steam which enters said auxiliary passage to the cylinder on the expansion side of the piston when compression is taking place on the opposite side of the piston.

In testimony whereof we have hereunto signed our names.

HUBERT J. TITUS.
JOHN S. WALLIS.
